UNITED STATES PATENT OFFICE

GUSTAVE M. NELL, OF DETROIT, MICHIGAN, ASSIGNOR TO CHICAGO PNEUMATIC TOOL COMPANY, OF NEW YORK, N. Y., A CORPORATION OF NEW JERSEY

PILE DRIVING APPARATUS

Application filed November 16, 1928. Serial No. 319,789.

This invention relates to apparatus for driving piles, posts, stakes, etc. and more particularly to apparatus which is adaptable for use with percussive hammer type machines not primarily intended for pile driving.

One object of the invention is to provide improved accessory apparatus for pile driving. Another object is to permit convenient replacement of parts which may become broken or damaged in service. Another object is to provide for application of the apparatus to a percussive machine in more than one position so that the position best suited to the work may be selected. Still another object is to prevent loss of driving power when the percussive machine becomes tilted in relation to the work. Other objects will be apparent from the detailed description which follows.

In order to illustrate the invention concrete embodiments thereof are shown in the accompanying drawings, in which:

Fig. 1 is a vertical sectional view of the apparatus applied to a percussive machine which is largely broken away, certain parts being shown in elevation;

Fig. 2 is an elevational view of the right-hand side of the lower portion of the apparatus shown in Fig. 1;

Fig. 3 is a sectional view generally similar to Fig. 1 disclosing a modification;

Figs. 4, 5 and 6 are plan and side elevational views taken at angles of 90° of the front head shown in Figs. 1 and 3.

The pile driving apparatus herein disclosed takes the form of an attachment applicable to certain percussive machines of the fluid pressure type such as pneumatic drills, or demolition tools, to adapt the same to the driving of piles, posts, stakes, and the like. The apparatus is intended to be applied to the front end of a percussive machine to take the place of the usual equipment and in general comprises a front head 7, cheek plates 8 and 9 secured to head 7 by suitable means such as bolts 10, and an anvil block 11 mounted in the bore of the front head 7. As shown in Fig. 1, front head 7 has a reduced portion 7a adapted for tele-

scoping engagement within the front end of cylinder A of a fluid pressure tool having an impact member or piston B. Head 7 has perforated ears 7b through which extend the side rods or through bolts C which hold the parts of the percussive tool in assembled relation. These bolts may extend through backhead D carrying manual supporting means for the machine such as a T handle E. Head 7, below ears 7b, is of polygonal shape in cross-section or plan, as indicated at Fig. 4. By preference it is square in shape and has axial grooves 7c (Figs. 1, 3, and 6) which permit the insertion of side rods C when the head is assembled upon the percussive machine. Head 7 also has upper and lower series of transverse bores 7d for bolts 10, the upper and lower series intersecting one another at right angles so that cheek plates 8 and 9 can be secured to either pair of opposing faces of the polygonal portion of members 7 as desired.

Cheek plates 8 and 9, shown in Fig. 1, form a front head extension, as indicated, and each has reverse bends at 12 and 13 respectively forming retaining shoulders which prevent the loss or ejection of anvil block 11. The restricted opening between cheek plates 8 and 9 beneath the bends provides a recess or socket adapted to receive the pile, post, or other object 0 upon which the work is to be performed. Either of the cheek plates, such as 8, may be bent to provide a rest or step 14 upon which the operator may place his foot or bear his weight to assist in the driving of member 0.

The upper or offset portions of the cheek plates 8 and 9 are clamped against the selected sides of the polygonal portion of front head 7 by bolts 10, as indicated. Means are provided for preventing the shearing of these bolts in the event that the same are not secured tightly or work loose in service. Such means preferably take the form of a cooperating lug or rib and socket arrangement on the head 7 and cheek plates 8 and 9. In the present instance the cheek plates each have a single lug or rib, 15 and 16 respectively, intermediate the upper and lower series of holes for bolts 10, such lugs or ribs

extending into the transverse sockets or grooves 7e provided therefor in member 7 (Figs. 1, 3, 5, and 6). By preference the cheek plates 8 and 9 have the top notches or recesses 17 and 18 respectively (Figs. 1 and 2) which receive the heads of the side rods C and lock the same against turning movement.

The modification of the invention shown in Fig. 3 is a similar in all respects to that shown in Fig. 1 save that anvil block 11a has additional guiding and retaining means associated with the cheek plates 8a and 9a, such means comprising extensions or bosses 11b slidably received in cooperating slots 8b and 9b of the respective cheek plates.

From the above it will be apparent that the feature of the polygonal portion on the front head with the cooperating cheek plates, which may be secured to any opposed pair of faces of the polygonal portion, permit the assembly of the front head extension upon a percussive machine, so that the supporting handle E for the latter will be parallel to or angularly associated with the object O, such work is to be performed, and that the plates carrying the step 14, may also be placed at any side of the machine. The cheek plates further are arranged to prevent turning of the through bolts so that the parts of the percussive machine cannot become loose in service. An additional feature lies in the fact that the lower face of either anvil block 11 or 11a is arranged to be rounded as indicated at 19 (Figs. 1 and 3) so that even if the machine becomes tilted somewhat upon the 45 While preferred forms of the invention have been herein shown and described, it is to be understood that the invention is not limited to the specific details thereof, but covers all changes, modifications, and adaptations within the scope of the appended claims.

I claim as my invention:

1. In apparatus for pile driving and the like including a percussive machine having an impact element with a front head secured to said machine and an anvil block supported by said head, and arranged to receive the blows of said element, means for adjustable attachment to said head to form an extension of the same and to provide a socket for the pile to be driven disposed either in line with or at an angle to the support for said machine.
2. In apparatus for driving piles, posts, and the like, including a percussive machine having an impact element, a front head secured to a pair of outer faces of said poly-
- cured to said machine and having a polygonal portion and a bore therethrough, an anvil block having a stem movably mounted in said head and arranged to receive the blows of said element, and extension means for said head attachable at will to any of the opposite pairs of sides of said polygonal portion to provide guide and retainer means for said block and a socket for the object to be driven.
3. In apparatus for driving piles, posts, and the like including a percussive machine having an impact element, a front head secured to said machine and having a polygonal portion and a bore therethrough, an anvil block having a stem movably mounted in said head and arranged to receive the blows of said element, plates secured to opposite sides of said polygonal portion to provide an extension for said head forming a socket for the object to be driven and guide and retaining means for said block, and interengaging guide means on said block and at least one of said plates comprising a projection on said block slidably received in an axial recess or slot in one of said plates.
4. In apparatus for driving piles, posts, and the like including a percussive machine having an impact element, a front head secured to said machine and having a polygonal portion and a bore therethrough, an anvil block having a stem movably mounted in said head and arranged to receive the blows of said element, plates secured to the outer sides of said polygonal portion to provide an axial extension for said head, one of said plates having an inwardly offset part beyond said head to provide a retainer wall for said block and cooperating with the other plate to protect a socket for the object to be driven.
5. In apparatus for driving piles, posts, and the like including a percussive machine having an impact element, a front head secured to said machine and having a polygonal portion and a bore therethrough, an anvil block having a stem movably mounted in said head and arranged to receive the blows of said element, plates secured to the outer sides of said polygonal portion to provide an axial extension for said head forming a socket beyond said head for the object to be driven and guide and retaining means for

cured to said machine and having a polygonal portion and a bore therethrough, an anvil block having a stem movably mounted in said head and arranged to receive the blows of said element, and extension means for said head attachable at will to any of the opposite pairs of sides of said polygonal portion to provide guide and retainer means for said block and a socket for the object to be driven.

3. In apparatus for driving piles, posts, and the like including a percussive machine having an impact element, a front head secured to said machine and having a polygonal portion and a bore therethrough, an anvil block having a stem movably mounted in said head and arranged to receive the blows of said element, plates secured to opposite sides of said polygonal portion to provide an extension for said head forming a socket for the object to be driven and guide and retaining means for said block, and interengaging guide means on said block and at least one of said plates comprising a projection on said block slidably received in an axial recess or slot in one of said plates.

4. In apparatus for driving piles, posts, and the like including a percussive machine having an impact element, a front head secured to said machine and having a polygonal portion and a bore therethrough, an anvil block having a stem movably mounted in said head and arranged to receive the blows of said element, plates secured to the outer sides of said polygonal portion to provide an axial extension for said head, one of said plates having an inwardly offset part beyond said head to provide a retainer wall for said block and cooperating with the other plate to protect a socket for the object to be driven.

5. In apparatus for driving piles, posts, and the like including a percussive machine having an impact element, a front head secured to said machine and having a polygonal portion and a bore therethrough, an anvil block having a stem movably mounted in said head and arranged to receive the blows of said element, plates secured to the outer sides of said polygonal portion to provide an axial extension for said head forming a socket beyond said head for the object to be driven and guide and retaining means for

onal portion to provide an axial extension for said head forming a socket for the object to be driven and guide and retaining means for said block, transverse securing members 5 extending through said head and said plates, and cooperating lug and recess means on said head and said plates to prevent shearing of said securing members.

7. In pile driving apparatus including a 10 percussive machine having an impact piston, a front head secured to said machine and having a polygonal portion extending therebeyond with an axial bore therethrough, an anvil block having a stem received in said 15 bore and a head beyond said polygonal portion, cheek plates secured to a selected pair of opposite faces of said polygonal portion to provide an extension inclosing said anvil head, said plates being shaped to provide a 20 restricted socket for the object to be driven and a retaining shoulder for said piston head, and transverse securing members extending through said head on opposite sides of said bore and through said plates.

25 8. In a fluid pressure percussive machine of the portable type having a cylinder, an impact piston reciprocable therein, and a front head having perforated ears with through bolts extending through said ears 30 for securing said head to said cylinder, said head beneath said ears being square and having axial grooves to permit the insertion of said bolts, and cheek plates secured to said head over said grooves and arranged to lock 35 the heads of said bolts against turning.

9. In a fluid pressure percussive machine of the portable type having a cylinder, an impact piston reciprocable therein, and a front head having perforated ears with 40 through bolts extending through said ears for securing said head to said cylinder, said head beneath said ears being square and having axial grooves to permit the insertion of said bolts, and cheek plates secured to said 45 head over said grooves and having notches or recesses receiving the heads of said bolts to hold the same against turning.

10. A front head for a portable percussive machine for adapting the latter to drive piles, posts, and the like, said head having a cylinder engaging part provided with perforated ears to receive the through bolts of the machine and a polygonal portion, said head having an axial bore therethrough to 55 receive the stem of an anvil block, said polygonal portion being arranged to have cheek plates secured to a pair of the outer sides thereof to form an axial extension of said head, said polygonal portion having 60 transverse bores through the solid portions thereof on opposite sides of said bore for securing members to hold the plates in place.

11. A front head for a portable percussive machine for adapting the latter to drive piles, posts, and the like, said head having a cyl-

inder engaging part provided with perforated ears to receive the through bolts of the machine and a polygonal portion, said head having an axial bore therethrough to receive the stem of an anvil block, said polygonal 70 portion being arranged to have cheek plates secured to a pair of the outer sides thereof and having transverse bores through the solid portions thereof on opposite sides of said bore for bolts to hold the plates in place, 75 said polygonal portion also having transverse recesses in the exterior thereof to receive projections on the cheek plates intended to prevent shearing of the bolts.

12. A cheek plate adapted to be secured to the front portion of a portable percussive machine, said plate having a bend providing offset portions in parallelism, one of said portions being adapted to engage said machine and having spaced rows of holes therethrough for bolts, a transverse lug or rib between said rows of holes to engage a complementary recess on the machine, the other portion of the plate being adapted to engage the work and the bend to form a retaining 90 shoulder for an impact member on the machine.

13. In apparatus for driving piles and like objects having flat tops, a percussive machine having a cylinder and an impact element reciprocable therein, a front head structure 95 providing a chamber for receiving the upper end of the object to be driven, and a single member movably supported by said structure and comprising the sole means for transmitting the blow of said impact element to the flat top of the object, said member having an enlarged elongate head disposed in the upper end of said chamber having a curved lower face to rest directly upon the 105 flat upper face of the object so as to deliver the blow thereto without substantial loss of force even if the machine engages the object at an angle.

Signed by me at Detroit, in the county of 110 Wayne and State of Mich., this 13th day of November, 1928.

GUSTAVE M. NELL.
